UNITED STATES PATENT OFFICE

114,345

DESIGN FOR A SWEATER

Louis A. Reitmeister, Great Neck, N. Y., assignor to Jenath Knitwear, Inc., a corporation of
New York

Application December 14, 1938, Serial No. 81,770

Term of patent 3½ years

To all whom it may concern:

Be it known that I, Louis A. Reitmeister, a citizen of the United States of America and resident of Great Neck, Long Island, county of Nassau, and State of New York, have invented a new, original, and ornamental Design for a Sweater, of which the following is a specification, reference being had to the accompanying drawing, forming part thereof.

In the drawing:

The figure is a front view of the sweater, the rear view being the same as the front view.

I claim:

The ornamental design for a sweater, substantially as shown.

LOUIS A. REITMEISTER.
